METHOD OF AND MEANS FOR REDUCING
THE EFFECTS OF UNDESIRED OSCILLA-
TIONS

David G. McCaa, Philadelphia, Pa.

Application October 29, 1930. Serial No. 492,055

4 Claims. (Cl. 250—20)

This invention relates to methods and means for separating desired oscillations from undesired oscillations according to their amplitudes regardless of their frequencies and particularly refers to methods of substantially reducing the effects of the undesired oscillations on the desired oscillations to a minimum. The invention is a modification of the methods described and claimed in my co-pending application, Serial No. 74,087, filed December 8, 1925 which has become Patent No. 1,814,051, granted July 14, 1931 and is a continuation in part thereof.

One object of the invention is to separate the desired and undesired oscillations into components, subject said components to a uni-directional electro-motive force of constant magnitude and substantially equal to the peak voltage of the desired oscillations, thereby multiplying the frequency of the undesired oscillations, and causing said components of multiplied frequency oscillations to oppose each other while the components of the desired oscillations are caused to add to each other, thereby increasing their amplitudes to affect a translating device.

25 A further object is to divide said desired and undesired oscillations into a pair of components, and again dividing each component into additional components multiplying the frequency of both the desired and undesired oscillations in the last-mentioned components, and causing the components of the multiplied frequency to oppose each other so as to have substantially no effect on a translating device and adding a uni-directional electro-motive force to the other of said components whereby the components of the desired oscillations are caused to combine cumulatively to affect translating device and the components of the undesired oscillations are caused to substantially oppose the other, thereby causing said translating device to be substantially unaffected by the undesired oscillations.

Other objects will appear hereinafter.

The organization and operation of the circuits of my invention will be understood from the drawings in which:

Fig. 1 is a schematic wiring diagram of the circuits of my invention, as applied to audio frequencies;

50 Figs. 2 and 3 are explanatory curves of the operation of my invention;

Fig. 4 is a diagram similar to that of Fig. 1 showing the invention applied to radio frequencies;

55 Fig. 5 is a modification wherein frequency multiplying transformers are used;

Fig. 6 is a further modification wherein rectifiers are used;

Figs. 7 and 8 are modifications wherein the invention is applied directly to the translating device;

60 Figs. 9 and 10 are explanatory curves; and

Fig. 11 is a system embodying successive frequency multipliers and filters.

Referring to Fig. 1, there are indicated two thermionic tubes V and V₁, each comprising an anode *a* and a hot filament or cathode *f*. Associated with the tubes are the magnetic field coils M and M₁, which, when traversed by a current, vary the impedance between the anodes and cathodes of the tubes, as well understood in the art. 70 The coils are connected in parallel branches to one terminal of the source S which represents a source of audio frequency currents of different amplitudes and of different characteristics, the lesser amplitude representing the desired signal 75 oscillations while the greater amplitude currents represent the undesired oscillations which may be atmospheric disturbances or any other electrical disturbances. The plate circuits of the tubes V and V₁ are the primaries *p* and *p*₁ and a 80 source of plate current B, the primaries *p* and *p*₁ opposing each other in their effect upon the secondary S', to which is connected the telephone instrument or any suitable sound reproducer. Between the terminal of source S and the coils M 85 and M₁ are inserted sources of unidirectional electro-motive forces E and E₁, the values of which may be varied by means of the potentiometer resistances *r*₂. The source E has its positive terminal connected to one end of the coil M, while the 90 source E₁ has the negative terminal connected to one end of the coil M₁. The other terminals of the coils M and M₁ are connected together and to the other terminal of the source S. The source S receives its energy from the output of the detector tube D which may be of the usual three electrode thermionic vacuum tube type which 95 detects the radio frequency currents collected by the antenna circuit AG and tuned by the condensers C and C₁. Heterodyne reception may be used if desired, in which case, a local source of alternating currents H is impressed on the input circuit to the detector tube D.

The operation of the system of Fig. 1 may be understood upon reference to Figs. 2 and 3. In 105 Fig. 2 the curve *m* represents an alternating current through the coil M and the curve *m*₁ represents the alternating current simultaneously existing in the coil M₁. The curve *p* shows the variation of current from the source B in the pri- 110

mary p for the current m in the coil M ; and similarly the curve p_1 represents the current from the source B through the primary p_1 for the current m_1 in the coil M_1 . As is apparent, the current im-
5 pulses p and p_1 are in phase and neutralize each other.

The system of Fig. 1 is rendered suitable for differentiating between the low and high amplitude currents from the source S by recourse to
10 the sources of electro-motive-force E and E_1 connected in opposite senses with respect to the source S in the circuits of the coils M and M_1 , respectively.

As indicated in the right-hand portion of Fig.
15 2, there is shown a curve m_2 which is the resultant of the curve m and electro-motive-force E . The source E in effect shifts the curve m upwardly so that it varies periodically between positive maxima and zero. Similarly, the curve m_3 shows
20 the effect of the electro-motive-force E_1 upon the current m_1 , shifting it entirely below the zero whereby the current through the coil M_1 varies from zero through successive negative maxima. The result upon the current through the primary
25 p is indicated by the curve p_2 and the effect upon the current through the primary p_1 is indicated by the curve p_3 . The curves p_2 and p_3 show that the currents through the primaries p and p_1 representative of the low amplitude current representing the signal now are in effect dephased 180 degrees with respect to each other and, therefore, act cumulatively upon the secondary S' , and, accordingly, the desired low amplitude signal-representing current affects the instrument T . Sim-
30 ultaneously, however, the interfering current of large amplitude has but slight effect upon the secondary S' . As indicated in Fig. 3, the halves of the interfering current of large amplitude are represented by the curves m_4 and m_5 passing re-
35 spectively through the coils M and M_1 . The feeble electro-motive-force E assists the current m_4 slightly, yielding a current represented by the curve m_6 , while simultaneously the electro-mo-
40 tive-force E_1 slightly opposes the current repre-
45 sented by the curve m_5 , yielding a current repre-
sented by the curve m_7 . As indicated by the arrows in Fig. 3, there is, therefore, but a slight resultant of the interfering current induced in secondary S' .

50 It is important to note that without sources E and E_1 , frequency doubling action occurs in primary windings P and P_1 when either is used separately with an alternating current input, and the waves of doubled frequency balanced out in sec-
55 ondary S' . This will be clear from an inspection of the curves p and p_1 of Fig. 2 and the curves of Fig. 9 to be described later. When sources E and E_1 are used, however, primaries P and P_1 each transfer a single frequency to secondary S' until
60 the input exceeds the potential of E and E_1 , when double frequency action commences. This will be apparent from an inspection of the curves of Fig. 3 and those of Fig. 10 described hereinafter.

In Fig. 4 is shown an arrangement similar to
65 Fig. 1 except that the source of alternating currents which traverse the coils M and M_1 is of radio frequency instead of audio frequency and the input of the detector tube is received from the coils p and p_1 . The operation of the systems
70 of both figures is fundamentally the same, includ-
ing the balanced frequency multiplying action.

In Fig. 5 is shown a system utilizing a pair of frequency multiplying transformers T and T_1 in balanced relation. The transformers comprise
75 pairs of primary windings M , M and M_1 , M_1 dis-

posed on outer cores A , C , A_1 , and C_1 and sec-
80 ondary windings S and S_1 disposed on cores B and B_1 midway between, the cores being joined by end pieces. The pairs of primaries are connected in series with secondaries S' and S_1' , respectively, of a transformer which represents a source of audio frequency currents. Between the secondaries S' and S_1' and the primaries M and M_1 are inserted sources of uni-directional electro-motive-force E and E_1 , the values of which may be varied by means of potentiometer resistances r_2 . The sources E and E_1 may be poled as indicated, provided the polarities of S' and S_1' are as indicated, on one half cycle. The secondaries S and S_1 are connected so as to oppose each other. Magnetizing windings W and W_1 are provided on cores B and B_1 and are connected in series with a source of uni-directional current B_2 .

In operation, the sense of direction or polarity of the fluxes set up by coils M and M_1 at any given instant is such that they add in series in each of the flux paths comprising cores A and C , and A_1 and C_1 . With equal fluxes set up by coils M and M_1 the terminals of cores B and B_1 are subjected to equal and opposite magnetic poles, so that no active flux exists in cores B and B_1 and no electro-motive-forces are developed in secondaries S and S_1 . The coils W and W_1 are used to establish a fixed flux in the cores and end pieces. Now it will be seen that on one-half cycle the fixed and
100 alternating fluxes will add in cores A and A_1 and oppose in cores C and C_1 , while on the next half cycle they will add in cores C and C_1 and oppose in cores A and A_1 . The result is that for every half cycle there appears in cores B and B_1 a
105 110 pulse in the same direction. The double frequency currents set up in secondaries S and S_1 by these pulses neutralize each other. This will be evident from the curves of Fig. 2 which apply equally here.

With uni-directional electro-motive-forces E and E_1 introduced, however, the low amplitude currents are dephased and act cumulatively, as shown in Fig. 2, while the large amplitude currents practically neutralize each other, as shown in Fig. 3, since the relatively small electro-motive-forces E and E_1 have little effect upon them.

In Fig. 6 is shown a system using rectifiers. A transformer T is provided having two pairs of primary windings M and M_1 on a common core
125 and secondary S . The coil pairs M and M_1 are wound oppositely, as shown, and are respectively connected in parallel relation with secondaries S' and S_1' of a transformer which represents a source of audio frequency currents. The induced
130 E. M. F.'s of S' and S_1' are of polarities as shown in the drawings during one-half cycle. Pairs of rectifiers R , R and R_1 , R_1 are connected in circuit with the primaries M and M_1 to provide alternate paths through the coils on each half cycle. In
135 circuit with the pairs of primaries are inserted sources of uni-directional electro-motive-force E and E_1 and potentiometer resistors r_2 , poled as shown.

It will be apparent that on the first half cycle
140 of current from S' and S_1' , current will flow through upper coils of M and M_1 , thereby setting up opposing fluxes in the core. On the next half cycle, current will flow through lower coils M and M_1 , thereby setting up opposing fluxes.
145 Without sources E and E_1 , the opposing fluxes would of course neutralize each other, and no effect would be had on secondary S . Either coil pair M or M_1 in the absence of the other would induce double frequency currents in secondary S ,
150

due to action of its associated rectifiers and the direction of the windings. With E and E_1 in circuit, however, the low amplitude signal currents are dephased and act cumulatively as shown in Fig. 2, while the large amplitude currents practically neutralize each other, as shown in Fig. 3.

Other arrangements for producing the same result as those previously described are shown in Figs. 7 and 8, wherein the multiplication of

frequency is produced in the sound reproducing device itself. In Fig. 7, the coils M and M_1 are the windings of non-polarized electro-magnet y and are wound so as to oppose each other in their effects on the non-polarized armature R , which actuates a drive rod q of a sound reproducer O . The action of coils M and M_1 on armature R may be readily understood by reference to Figs. 2 and 3. In Fig. 2, the arrows indicate the direction of the forces simultaneously acting upon armature R . It will be noted that when sources E and E_1 are absent, the forces of attraction are of double frequency but of opposite phase and, therefore, have no effect on the armature. For each alternation of the current, coils M and M_1 exert two pulls on the armature in opposite directions, each in a single direction. By introduction of sources E and E_1 , however, the low amplitude signal currents are dephased, as shown in Fig. 2, and coils M and M_1 act cumulatively on armature R . Simultaneously, the large amplitude currents have but slight effect on the armature, since they cause coils M and M_1 to exert substantially equal and opposite forces thereon, as indicated by the arrows in Fig. 3.

In Fig. 8 is shown a transformer having secondaries S' and S_1' which represents a source of audio frequency currents. Permanent magnets T and T_1 are disposed as shown and have mounted thereon armature R and pole pieces A , B , C , and D . The armature actuates a drive rod q of a sound reproducer O . The pole pieces receive magnetic flux of similar sign and of equal strength from the permanent magnets. A pair of coils M are wound on pole pieces B and C , while a similar pair M_1 are wound on pole pieces A and D . The coil pairs are connected respectively to secondaries S' and S_1' . Sources of uni-directional electro-motive-force E and E_1 are connected to the respective coil pairs.

Neglecting sources E and E_1 , coils M_1 are so connected that on one-half cycle of current pole piece A has a flux set up therein that adds to the permanent flux from magnet T_1 , while pole piece D has a flux established in it that opposes the permanent flux from T_1 . Simultaneously, pole piece B has a flux set up therein by coil M that adds to the permanent flux from magnet T , while pole piece C has a flux that opposes the flux from T . As a result, the permanent flux is shifted out of C and D into A and B . On the next half cycle, these relations reverse and pole pieces C and D become the main flux path. The result is then that on one-half cycle, pole pieces A and B exert equal and opposite stresses on armature R , while on the next half cycle, pole pieces C and D exert equal and opposite stresses on armature R . This will be more clear by reference to Fig. 2, wherein the arrows again represent the forces acting on the armature. Either of the coil systems M or M_1 acting alone in connection with its magnet T or T_1 constitutes a polarized frequency changer. With sources E and E_1 in circuit, however, and with the polarities of S' and S_1' as shown, the low amplitude signal

currents are dephased, as shown in Fig. 2, the current in coils M_1 going to zero when the current in coil M is a maximum and vice versa. The arrows indicate the cumulative stresses on the armature. Pole pieces A and C act cumulatively on the armature, while the flux in pole pieces B and D aids the action of A and C . The large amplitude currents, however, continue to produce substantially equal and opposite effects on the armature R , as shown in Fig. 3.

It should be noted that in the systems of Figs. 5, 7 and 8, wherein magnetic flux relations are relied upon, the same result may be obtained by providing flux biases to dephase the flux instead of using electro-motive-forces E and E_1 . In such case, adjustable constant fluxes would be provided to bias the fluxes set up by currents from the audio frequency source. The curves of Figs. 2 and 3 are applicable to such a system but must be considered as flux curves.

The operation of the system of Figs. 1 and 4 may be explained in another manner by means of the graphs of Figs. 9 and 10. Fig. 9 is a diagram of the magneto-motive-forces in coils M and M_1 plotted against the plate to filament impedances of the tubes V and V_1 . These characteristics are plotted without the sources E and E_1 being in the circuit. The curve a represents the desired or signal oscillations while curve b represents the undesired oscillations which may be atmospheric disturbances and whose amplitude is many times greater than the signal amplitude. It will be seen from this diagram that the desired oscillations a produce a plate current flow in the primary p_1 , which is represented by the curve a_1 which is a pulsating current of double the original frequency. A similar plate current represented by curve a_2 is produced in the primary p , which is of equal amplitude and frequency but of opposite phase. These currents a_1 and a_2 , therefore, neutralize each other completely. The currents b , which are of higher amplitude, produce plate currents b_1 and b_2 which are also of the same frequency and amplitude but opposing phase producing a zero resultant.

In Fig. 10 is illustrated the action which takes place when the biasing electro-motive-forces E and E_1 are introduced into the circuits of the coils M and M_1 . The sources E and E_1 are of a magnitude equal to the peak potential of the desired oscillations and are arranged so that E offsets the characteristic of the tube V from its normal position in the positive direction by an amount equal to the peak voltage of the desired oscillations while the source E_1 offsets the characteristic of tube V_1 in the negative direction by the amount equal to the peak potential of the signal currents. It will now be noted that the plate currents produced in coils p and p_1 represented by curves a_2 and a_1 are of the same frequency as the signal current a and of the same amplitude and phase, while the plate currents produced by the undesired oscillations b are of opposite phase, as indicated by b_1 and b_2 , and frequency doubling occurs. The peaks of b_1 and b_2 differ slightly in value so that there is not a complete neutralization, but a resultant current b_3 is produced, the amplitude of which is no greater than that of a_2 and includes currents of several different frequencies which are in general the harmonics of the original frequency. The amplitudes of b_3 being brought to the same level as those of a_2 , are, therefore, substantially imperceptible as compared to their original amplitudes.

represented by the curve *b*. From the analysis of the diagram of Fig. 10, it will, therefore, be noted that when the uni-directional electro-motive-forces *E* and *E₁* are introduced that the frequency of the desired oscillations remains unchanged, but their amplitude is doubled while the frequency of the undesired oscillations is multiplied and the multiplied frequencies are made to oppose each other to such an extent as to substantially reduce their effects on the secondary *s*.

10 It will be noted that the wave *b₃* is not a sine wave but contains harmonics of the resultant signal wave *a₃*. The wave *b₃* may be passed through a filter but a higher amplitude wave results. If this latter wave is again passed through a balanced frequency raising device and a filter, a lower amplitude wave will be obtained. This operation may be repeated until a wave similar in shape and amplitude to the signal wave *a₃* is 15 obtained. Since a wave of the shape of *b₃* represents greater energy than wave *a₃*, it is desirable to subject it to the repeated frequency raising and filtering operation.

20 Such a system is shown in Fig. 11, wherein the output of a radio receiver is subjected to successive stages of balanced frequency raising and filtering. The balanced frequency raisers may, of course, comprise any suitable device, such as any of those disclosed. Likewise, the filters 25 may be of any suitable type. The balanced frequency raising operation may be considered a cutting off operation, since it really cuts the disturbance wave down to signal amplitude. Therefore, the process is one which comprises repeatedly cutting off and filtering the wave until the 30 desired wave is obtained.

35 While I have shown specific embodiments of my invention for the purpose of description of its principles of construction and operation, it 40 is apparent that various changes could be made therein without departing from the scope of the invention. I desire, therefore, that only such limitations shall be imposed thereon as are indicated in the appended claims.

45 I claim:

50

55

60

65

70

75

1. Means for reducing the effects of undesired oscillations on desired oscillations comprising a source of said desired and undesired oscillations, means for dividing said oscillations into components, means comprising a plurality of transformers for multiplying the frequency of the components of the undesired oscillations by an integral number, and means for causing said components of multiplied frequency to oppose each other whereby they are substantially reduced in 80 their effects on a translating device.

2. Means for reducing the effects of undesired oscillations on desired oscillations comprising a source of said desired and undesired oscillations, means for dividing said oscillations into components, means comprising a plurality of rectifier devices for multiplying the frequency of the components of the undesired oscillations by an integral number, and means for causing said components of multiplied frequency to oppose each 90 other whereby they are substantially reduced in 95 their effects on a translating device.

3. A system for reducing the effects of undesired oscillations on desired oscillations comprising a source of said desired and undesired oscillations, means for repeatedly multiplying the frequency of said undesired oscillations by an integral number and for causing them to oppose each other after each frequency multiplying operation whereby resultant waves are obtained after 100 each frequency multiplying operation, and means for filtering said waves after each frequency multiplying operation.

4. A method for reducing the effects of undesired oscillations on desired oscillations which 110 comprises successively dividing said oscillations into components, multiplying the frequency of the components of the undesired oscillations by an integral number, and causing said components of multiplied frequency to oppose each other 115 after each frequency multiplying operation whereby a resultant wave is obtained after each frequency multiplying operation, and filtering said wave after each frequency multiplying operation.
